CUTTING TOOL

John F. Wulff, Westfield, N. J., assignor to
 Western Electric Company, Incorporated, New
 York, N. Y., a corporation of New York

Application September 11, 1937, Serial No. 163,381

3 Claims. (Cl. 30—156)

This invention relates to a cutting tool and more particularly to a tool for cutting sheet material.

There is an innumerable number of places and conditions, under which it is desired to cut pieces of sheet material, paper, cellulose products, gold leaf, other metallic foils, textiles, films, etc., etc., by hand on a table top, board or other appropriate support.

10 An object of the present invention is to produce a simple, handy and reliable device or tool for such use with an interchangeable cutting blade, in which the blade is automatically completely housed except when in use.

15 With the above and other objects in view one embodiment of the invention may comprise a housing adapted for comfortable manual handling having a chamber within which a sharp edges blade is pivotally mounted to be completely retired within the housing when not in use, and provided with means to cause a portion of the edge of the blade to protrude from the housing while in use only.

20 Other objects and features of the invention will appear from the following detailed description of one embodiment thereof taken in connection with the accompanying drawing in which the same reference numerals are applied to identical parts in the several figures and in which

30 Fig. 1 is a broken view in side elevation of a tool constructed in accordance with the invention;

Fig. 2 is an exploded plan view thereof;

Fig. 3 is a detached view in side elevation of the body of the tool;

Fig. 4 is a detached view in end elevation of the blade and its control member;

Fig. 5 is a detached view in side elevation of the cover plate, and

40 Fig. 6 is a detached view in side elevation of the blade.

The embodiment of the invention herein disclosed comprises a body 20 formed with a recess or chamber 21 and an integral handle 22. This body may be made of any suitably rigid material, metal, wood, molded plastic such as Celluloid or artificial resin, or other appropriate substance. The bottom wall of the recess 21 is pierced with a perforation 24 and a slot 25. There is also a bore 26 extending down inside the body from its top surface and substantially parallel to and intersecting longitudinally the slot 25.

45 A little to the right of the recess 21 is a stop shoulder 27, against which may be abutted the correspondingly formed right hand edge 28 of

a cover plate 29 formed to match the outline of the body 20 and to fit thereon to cover the recess 21. When in place, this cover plate may be held by a bolt 30 and nut 31, the bolt passing snugly through the perforation 24 and through a corresponding perforation 32 in the cover plate.

The recess 21 is made to be little deeper than the thickness of an ordinary double edged razor blade 34 of the type shown in Fig. 6 and generally familiar under such trade-marks as "Gilette," "Probak," etc. Such blades are commonly manufacture and sold to fit various commercial safety razors and have a generally uniform size and shape. Further they are customarily provided with at least two round perforations, 10 or with one perforation 33 having an elongated form whose ends are relatively located in the blade where the two perforations of the other type are. The two opposite longer edges of the roughly rectangular blade are sharpened.

20 The two ends of the recess 21 are so formed and the perforation 24 is so located that when a razor blade as described is located flat in the recess with the bolt 30 passing through one end of the perforations 33 as well as through the 25 perforations 24 and 32, the blade 34 may swing pivotally on the bolt as indicated in Fig. 1 to be either completely contained within the body 20 as a housing or to protrude its left end slightly from the bottom of the housing. The bolt 30 is 30 however made somewhat smaller in diameter than the rounded end portion of the slot 33 so that the blade 34 may slide a little on the bolt as well as pivot thereon.

35 The stem 35 of a push button 36 is slidable in the bore 26 and so also longitudinally in the slot 25. A screw 37 passes through the left end of a slot 40 and through the slot 25 and is mounted in the lower part of the stem 35. The head of this screw is too large to pass through the slot 33 and so holds the blade 34 pivotably to the 40 stem 35. The button 36 is normally held in the upper position shown in Fig. 1 by a leaf spring 38 mounted as shown, on the body 20 by screws 39.

45 By pushing down on the button 36 with the thumb or a finger while holding the body 20 or handle 22 in the hand, the left lower corner of the blade is forced to protrude from the body into operative position as shown in dotted lines in Fig. 1. Although the bore 26 is straight and not arcuate, the blade, pivoted at 30 is free to slide on the bolt 30 as described above, sufficiently to allow the screw 37 to follow the straight line motion of the stem 35 in the bore 26.

50 The cover plate 29 is formed with the slot 40 55

located over and parallel to the slot 25 of sufficient width to receive the head of the screw 37.

When a blade 34 is dulled by use at one corner, removal of the plate 29 and screw 37 will permit the blade to be turned end for end or side for side or both to bring a fresh corner into use, or a new blade may then be conveniently substituted.

It will be noted that the blade is normally completely housed within the body 20 except when the button 36 is pushed down and held down; and if the tool be laid aside, or the button released, the blade is immediately retracted within the housing. Thus the blade is never exposed except by intention. At the same time exposure of the blade for use is effected simply and in a natural, untiring and convenient manner.

The embodiment of the invention herein disclosed is merely illustrative and may well be departed from and modified in many ways without departing from the scope and spirit of the invention as pointed out in and limited solely by the appended claims.

What is claimed is:

25 1. The combination with an apertured double edged razor blade or the like, of a body having a chamber therein, a fixed pivot and a reciprocable pivot disposed in the chamber and positioned to

be receivable in apertures in the said blade for movement of the blade about the fixed pivot by the reciprocable pivot from a safety position entirely within the body to a cutting position with a portion of an edge of the blade protruding beyond the body. 5

2. A safety cutting tool comprising a body having a chamber therein, a fixed pivot positioned in the chamber, a reciprocable pivot positioned in the chamber, and a double edged blade apertured to receive and be removably mounted on both pivots for movement about the fixed pivot by the reciprocable pivot from a safety position entirely within the body to a cutting position with a portion of an edge of the blade protruding beyond the body. 10

3. A safety cutting tool comprising a body having a chamber therein, a fixed pivot positioned in the chamber, a reciprocable pivot positioned in the chamber, and a blade having a plurality of cutting edges and apertured to receive and be mounted in selective positions on both pivots for movement about the fixed pivot by the reciprocable pivot from a safety position within the body to a cutting position with a portion of one 25 of the edges protruding beyond the body.

JOHN F. WULFF.
